4 Claims. (Cl. 62—119.5)

1

My invention relates to refrigerators of the absorption type, and more particularly to cooling of a storage compartment of a refrigerator with the aid of a refrigeration system employing evaporation of refrigerant fluid in the presence of an inert gas or auxiliary agent.

It is an object of my invention to effect improvements in cooling a storage compartment of a refrigerator by a refrigeration system of the inert gas type, particularly to provide a cooling element for such a system which will make available a maximum amount of usable storage space in the compartment.

Another object of my invention is to provide such a cooling element which can be inserted into and removed from the storage compartment through an opening in a thermally insulated wall thereof which is of minimum size, thereby reducing the tendency for heat transfer into the compartment at the closure member employed to close the wall opening and promoting efficient cooling of the compartment by the cooling element.

The above and other objects and advantages of the invention will be better understood from the following description taken in connection with the accompanying drawings forming a part of this specification, and in which Fig. 1 is a view more or less diagrammatically illustrating an absorption refrigeration system of the inert gas type in which the invention is embodied; Fig. 2 is a fragmentary vertical sectional view of a refrigerator and cooling element therefor which embodies the invention and is associated with a refrigeration system like that shown in Fig. 1; Fig. 3 is a horizontal sectional view taken at line 3—3 of Fig. 2 to show details more clearly, the cooling element being seen in top plan view; Figs. 4 and 5 are top plan views of cooling elements illustrating modifications of the embodiment shown in Figs. 2 and 3; Fig. 6 is a front view in elevation of a cooling element illustrating a still further modification of the invention in which provision is made for freezing ice cubes and the like; and Fig. 7 is a vertical sectional view of a cooling element illustrating a still further modification of the invention.

In Fig. 1 I have shown my invention in connection with an absorption refrigeration system of a uniform pressure type which is well known in the art and in which an inert pressure equalizing gas is employed. Such a refrigeration system comprises a generator or boiler 10 containing a refrigerant, such as ammonia, in solution in a body of absorption liquid, such as water. Heat may be

2

supplied to the boiler 10 from a heating tube or flue 11 thermally connected therewith, as by welding. The heating tube 11 may be heated in any suitable manner, as by a liquid or gaseous fuel burner 12, for example, which is adapted to project its flame into the lower end of the tube.

The heat supplied to the boiler 10 and its contents expels refrigerant vapor out of solution, and the vapor thus generated flows to an air cooled condenser 14 in which it is condensed and liquefied. Liquid refrigerant flows from condenser 14 through a conduit 15 into a cooling element 16 in which it evaporates and diffuses into an inert pressure equalizing gas, such as hydrogen, which enters the lower part thereof from a gas heat exchanger 17. Due to evaporation of refrigerant fluid into inert gas, a refrigerating effect is produced with consequent absorption of heat from the surroundings.

20 The rich gas mixture of refrigerant vapor and inert gas formed in cooling element 16 flows from the upper part thereof through a conduit 18, gas heat exchanger 17, conduit 19 and absorber vessel 20 into the lower part of an absorber coil 21. In 25 absorber coil 21 the rich gas mixture flows countercurrent to downwardly flowing absorption liquid which enters through a conduit 22. The absorption liquid absorbs refrigerant vapor from inert gas, and inert gas weak in refrigerant 30 flows from the upper part of absorber coil 21 in a path of flow including the gas heat exchanger 17 into the lower part of cooling element 16.

Absorption solution flows downwardly through coil 21 into the absorber vessel 20 and such solution, which is enriched in refrigerant, passes from the vessel through a conduit 23 and an inner passage or pipe 24 of liquid heat exchanger 25 into the lower end of a vapor lift pipe or tube 26 which is in thermal exchange relation with the 35 heating tube 11, as by welding. Liquid is raised by vapor-liquid lift action through pipe 26 into the upper part of boiler 10. Refrigerant vapor expelled out of solution in boiler 10, together with refrigerant vapor entering through pipe 26, flows 40 upwardly from the boiler to the condenser 14, as previously explained.

The outlet end of condenser 14 is connected by an upper extension of conduit 15 and a conduit 50 27 to a part of the gas circuit, as to the upper part of absorber coil 21, for example, so that any inert gas which may pass through the condenser 14 can flow into the gas circuit. The absorption liquid from which refrigerant vapor has been 55 expelled flows from the boiler 10 through a connec-

tion 28, an outer pipe or passage 29 of the liquid heat exchanger 25 and conduit 22 into the upper part of the absorber coil 21. The circulation of absorption solution in the liquid circuit just described is effected by raising of liquid through pipe 26.

In order to simplify Fig. 1, the cooling element 16 has been illustrated apart from a household refrigerator. The manner in which cooling elements of absorption refrigeration systems like that just described are positioned in a storage compartment of a household refrigerator cabinet is diagrammatically shown in Figs. 2 and 3. In Figs. 2 and 3 the cooling element 16 is disposed in a storage compartment 30 having a top wall 32, rear wall 33 and opposing side walls 34, only one of which is shown in Fig. 3.

In order to position the cooling element 16 in the storage compartment 30, the rear wall 33 of the cabinet is formed with an opening 35 defined by a rectangular frame 36 which may be formed of wood, for example. A cover or closure member 37 for the opening, which contains insulating material 38 and through which the conduit 15 and gas heat exchanger 17 extend, is arranged to bear against a gasket 39 of suitable insulating material and removably secured at 40 to the rear wall 33.

While the cooling element 16 in Fig. 1 is diagrammatically shown in the form of a looped coil in a single vertical plane, it should be understood that this is the customary practice when schematically illustrating an absorption refrigeration system of the inert gas type. However, in cooling elements formed of piping and shaped to provide a path of flow for inert gas which extends through a substantial vertical height, it has generally been the practice heretofore to employ a looped coil having horizontally spaced apart straight portions which are disposed one above another in different vertical planes and connected by horizontal as well as vertical bends. In such cooling elements provision is usually made to provide supporting surfaces which are in good heat conductive relation with the spaced apart straight coil portions and bridge the gap therebetween and upon which trays can be placed for freezing ice and other matter, as well as to fix fins to the straight portions in the same horizontal plane to provide a relatively extensive heat transfer surface for cooling air in a storage compartment. A cooling element of this general kind is shown and described, for example, in United States Letters Patent No. 2,320,502 to Tage Schullstrom.

In some cases cooling elements of the kind disclosed in the Schullstrom patent are not entirely satisfactory in that a substantial part of the storage compartment is taken up by the cooling element, thereby reducing the amount of space available for storing foods. This is especially true in refrigerator cabinets of small size having a storage compartment ranging from one to three cubic feet, for example.

In accordance with my invention, in order to provide a maximum amount of usable storage space in the compartment 30, the cooling element 16 comprises a looped coil having straight portions 41 one above another and connecting bends 42' disposed essentially in a single vertical plane. As best shown in Fig. 3, the looped coil is desirably positioned closely adjacent to and alongside one of the lateral side walls 34 so that the compartment 30 can be efficiently used for a

variety of different food loadings and readily accommodate articles which are of large size.

A vertically extending plate 42 having an area coextensive with that of the looped coil is secured in good thermal contact with the coil along its entire length, as by welding or brazing, for example, to provide a relatively extensive heat transfer surface over the opposing faces of which air can pass in intimate contact therewith. The plate 42 desirably is fixed to the looped coil at the side thereof removed from the side wall 34 of the storage compartment 30, and the forward edge portion may be bent back so as to envelop the front connecting bends 42', as indicated at 43, thereby forming a simple arrangement for concealing the looped coil from view and providing a cooling element which is attractive and neat in appearance.

By locating the cooling element 16 closely adjacent to one of the side walls 34 so as to form a relatively narrow passage 44 having a vertical height coextensive with that of the looped coil, the natural circulation of air, which is induced by air coming in contact with the looped coil and plate 42, is promoted. In addition, a number of vertically extending L-shaped fins 45 may be secured in good thermal contact with the plate 42, which not only increase the heat transfer surface provided by the cooling element 16 but also form a plurality of open-ended U-shaped channels 46 which further promotes natural circulation of air in the compartment 30 as the result of air movement in the channels.

If desired, a plate may be provided which is of U-shaped form and in good thermal contact with both sides of the vertically extending looped coil. Such a modification is shown in Fig. 4 in which a plate 42a envelops the forward part and both sides of the looped coil. In addition, vertically extending L-shaped fins 45a may be secured in good thermal contact with the plate 42a at both sides of the looped coil to provide open-ended U-shaped channels 46a at opposite sides of the cooling element.

In certain instances it may be preferable to provide cooling elements in accord with the invention in which the L-shaped fins are secured directly to the looped coil, thereby avoiding the necessity of using plates 42 and 42a in the embodiments of Figs. 2 and 3, respectively. Such a modification is shown in Fig. 5 in which the sides 47 of L-shaped fins 45b more or less form a substantially continuous plate-like surface which provides a relatively extensive heat transfer surface and the open-ended channels 46b. In Fig. 5 the L-shaped fins 45b serve to conceal the looped coil from view and in certain instances it may be preferable to provide such fins only at the side of the looped coil removed from the lateral side wall of the storage compartment, that is, on the same side of the looped coil as the L-shaped fins 45 in Fig. 3.

A cooling element formed of a looped coil in a single vertical plane readily lends itself to a construction for supporting an ice tray for freezing ice and other matter. Such a modification is shown in Fig. 6 in which two plates 42b and 42c are disposed one above another in good thermal contact with upper and lower portions, respectively, of the looped coil. The upper plate 42b is bent back and envelops the uppermost straight coil portion 41, as indicated at 48, and L-shaped fins 45c may be secured thereto. The bottom part of plate 42b is formed to provide a recep-

tacle 49 which is centrally disposed relative to the looped coil.

The lower plate 42c envelops the two bottom straight coil portions and fins 45d are secured thereto. The receptacle 49 is adapted to receive an ice tray 50 and the bottom supporting surface thereof is in good thermal contact with the upper bent portion of the bottom plate 42c, so that a good heat conductive path will be provided for abstracting heat from the contents of the tray 50. A front plate 51 having an opening 52 therein through which the tray 50 can be inserted into and withdrawn from the receptacle 49 may be provided at the front of the looped coil and fixed to the cooling element in any suitable manner.

In Fig. 7 I have shown a modification in which an ice tray 50 is adapted to be placed on a plate 49a in direct thermal contact with a straight portion of the looped coil, thus eliminating the necessity of shaping a plate member to form a receptacle as shown in Fig. 6 and just described. In this modification plates 42e and 42f are secured to one side of the looped coil and L-shaped fins 45e and 45f in turn are fixed thereto generally in the same manner as shown in Fig. 6.

In view of the foregoing, it will now be understood that an improved cooling element or evaporator structure has been provided for absorption refrigeration systems of the inert gas type which comprises a looped coil having substantially horizontal straight portions and connecting bends in a single vertical plane. When such an evaporator structure is disposed in a storage compartment of a household refrigerator, especially in a refrigerator cabinet which is relatively small in size, a maximum amount of usable storage is provided in the compartment.

Further, an evaporator structure constructed in accord with the invention possesses the additional important advantage that it can be inserted into and withdrawn from the storage compartment through an opening in a thermally insulated wall of the compartment which is of minimum size and whose height is considerably greater than its width. Such openings, which are often referred to as "window openings," desirably should be as small as possible to minimize the tendency for heat transfer into the storage compartment about the thermally insulated closure member which closes and seals the "window opening."

In Figs. 2 and 3 it will be seen that the "window opening" is relatively narrow and of such height that it will be just sufficiently large to accommodate the looped coil and heat transfer fins in thermal contact therewith. Moreover, by locating the looped coil adjacent to a lateral side wall of the storage compartment and concealing such coil from view when access is gained into the compartment by opening the door at the front of the cabinet, a cooling arrangement is obtained which is neat and attractive in appearance and permits a wide variety of food loadings. This is especially important in small cabinets having storage compartments which are about one to one and a half cubic feet in size and employed to cool bottled beverages or to store medicines, such as serums, for example. It will be seen that all of the piping or conduit means located in the compartment 30 is disposed substantially in a single vertical plane that is perpendicular to the thermally insulated wall 33 having the relatively narrow vertical extending opening 35. Hence, the entire portion of the gas circuit in the com-

partment 30 is formed by piping which provides a path of flow for refrigerant fluid and inert gas in which such fluids in their movement therethrough always remain essentially in the single vertical plane.

Modifications of the embodiments of my invention which I have described will occur to those skilled in the art, so that I desire my invention not to be limited to the particular arrangements set forth and intend in the claims to cover all modifications which do not depart from the spirit and scope of the invention.

What is claimed is:

1. In a refrigerator including a cabinet having thermally insulated walls defining a storage compartment and in one of which a relatively narrow vertically extending opening is provided whose height is considerably greater than its width, and a thermally insulated closure member for such opening, absorption refrigeration apparatus including piping providing a circuit for inert gas comprising a cooling element located in the compartment and removable therefrom with removal of the closure member, the piping for said cooling element being in the form of a looped coil in which refrigerant fluid evaporates in the presence of the inert gas, and all of the piping located in the compartment including said looped coil being disposed essentially in a single vertical plane that is substantially perpendicular to the thermally insulated wall having the relatively narrow vertically extending opening, said looped coil being disposed closely adjacent to and spaced from a lateral side wall of the compartment and including horizontally extending straight portions at different levels and connecting vertical bends, structure in good thermal contact with said looped coil to provide a relatively extensive heat transfer surface over which air can pass in intimate contact so as to promote cooling of air, and a substantially flat member mounted on a straight coil portion beneath a higher located straight coil portion and in good thermal connection therewith, said flat member being adapted to support an ice tray and extending transversely of the vertical plane of said looped coil and having a region thereof in vertical alignment with said structure providing said relatively extensive heat transfer surface.
2. In a refrigerator including a cabinet having thermally insulated walls defining a storage compartment and in one of which a relatively narrow vertically extending opening is provided whose height is considerably greater than its width, and a thermally insulated closure member for such opening, apparatus having a circuit for inert gas which includes a cooling element located in said storage compartment and removable therefrom with removal of the closure member, said cooling element comprising a looped coil disposed essentially in a single vertical plane which is substantially perpendicular to the thermally insulated wall having the relatively narrow vertically extending opening and in which refrigerant fluid evaporates in the presence of the inert gas, said looped coil being disposed closely adjacent to and spaced from a lateral side wall of the compartment, and structure in good thermal contact with said coil to provide a relatively extensive heat transfer surface, said structure being constructed and arranged to provide a number of open-ended vertically extending channels coextensive in height with said coil to promote natural circulation of air induced by air coming in contact with the surfaces of said coil and channels.

3. In a refrigerator including a cabinet having thermally insulated walls defining a storage compartment and in one of which a relatively narrow vertically extending opening is provided whose height is considerably greater than its width, and a thermally insulated closure member for such opening, absorption refrigeration apparatus including piping providing a circuit for inert gas comprising a cooling element located in the compartment and removable therefrom with removal of the closure member, the piping for said cooling element being in the form of a looped coil in which refrigerant fluid evaporates in the presence of the inert gas, and all of the piping located in the compartment including said looped coil being disposed essentially in a single vertical plane that is substantially perpendicular to the thermally insulated wall having the relatively narrow vertically extending opening, said looped coil including horizontally extending straight portions one above another and connecting bends, structure including a vertically extending part in good thermal contact with a plurality of said straight portions at different levels to provide a relatively extensive heat transfer surface over which air can pass in intimate contact so as to promote cooling of air, such vertically extending part having a gap between adjacent straight portions of said coil, and a plate mounted on the lower of said adjacent straight coil portions at the gap and in good thermal connection therewith, said plate being adapted to support an ice tray and extending transversely of the vertical plane of said looped coil and having a region thereof in vertical alignment with said vertically extending part providing the relatively extensive heat transfer surface.

4. In a refrigerator including a cabinet having thermally insulated walls defining a storage compartment and in one of which a relatively narrow vertically extending opening is provided whose height is considerably greater than its width, and a thermally insulated closure member for such

5 opening, absorption refrigeration apparatus including piping providing a circuit for inert gas comprising a cooling element located in the compartment and removable therefrom with removal of the closure member, the piping for said cooling element being in the form of a looped coil in which refrigerant fluid evaporates in the presence of the inert gas, and all of the piping located in the compartment including said looped coil being disposed essentially in a single vertical plane that is substantially perpendicular to the thermally insulated wall having the relatively narrow vertically extending opening, said looped coil including horizontally extending straight portions one above another and connecting bends, structure including a horizontally disposed part in good thermal contact with a horizontally extending straight portion which is beneath the uppermost straight portion of said coil for supporting an ice tray and the like and a vertically extending part in good thermal contact with a plurality of straight portions at different levels and over which air can pass in intimate contact therewith, said vertically extending part being entirely below and in good thermal connection with said horizontally extending part.
